PROCESS FOR THE PYROLYSIS AND GASIFICATION OF HYDROCARBONACEOUS MATERIALS

Maxwell Patrick Sweeney, Philadelphia, Pa., assignor to United Engineers & Constructors Inc., Philadelphia, Pa., a corporation of Delaware

Application February 17, 1956, Serial No. 566,205

17 Claims. (Cl. 208—53)

This invention pertains to a method for the production of valuable gaseous, liquid, and solid products from lower value hydrocarbonaceous materials, and particularly to a method for the pyrolysis of hydrocarbonaceous substances, in the presence of finely divided solid material, without the disadvantages normally associated with the use of such material.

The invention is of use in many different applications; for example in the production of valuable gaseous and liquid products and coke from petroleum residues and low value gaseous hydrocarbons, in the gasification and carbonization of coal, lignite and peat and in petroleum refining.

Prior to the present invention a number of processes have been suggested for converting lower value hydrocarbonaceous materials, such as lower paraffins, residual fuel oils and coal, to more valuable gaseous and liquid products, and coke.

In general, these processes have been run at three different temperature ranges, below about 1100° F., above 1800° F. and in the intermediate range between about 1100° F. and about 1800° F.

Below about 1100° F., the products are primarily lower molecular weight normally liquid paraffinic hydrocarbons.

Above about 1800° F. the products are largely carbon and normally gaseous materials having a high acetylenic content.

In the range between about 1100° F. and about 1800° F. the proportion of aromatic substances is large, increasing with increasing temperature, above about 1100° F. and reaching a maximum around 1500° F. These aromatic materials have a high sale value and in most cases are the most desirable product. However, many of the aromatics so produced tend to polymerize in the presence of other pyrolysis products and at the temperatures in question, i.e. 1100° F. to 1800° F., to produce high molecular weight liquid pitch.

The question how best to control the several reactions involved and to collect the large variety of different products formed has given rise to a number of different techniques for conducting pyrolysis processes in this temperature range and for furnishing the heat necessary for the pyrolysis.

It has been proposed, for example, to charge the low cost hydrocarbonaceous feed to a fluidized bed of finely divided solids maintained at pyrolysis temperature and to conduct all of the cracking in the bed. The difficulty with this technique is that it is inherently inflexible. Reaction time, temperature, and other conditions vary with different feed materials and products, and it is desirable to have an apparatus capable of handling a variety of different feeds to make a variety of different products. Vessels suitable for holding a fluidized bed must, however, be designed for a limited range of operating conditions, and are not easily altered to different conditions. Moreover, in many instances it is desirable to quench the

2

intermediate products and prevent the pyrolysis reaction from going to completion. This cannot conveniently be done with a single fluidized bed.

It has also been proposed to conduct the pyrolysis reaction in a hot moving stream of gases and entrained solids and then deliver the reacted stream into a suitable separation device, such as a cyclone separator, where the vaporous pyrolysis products would be separated from the solids. Processes of this type have the drawback that they are difficult to control to give products of uniform composition. Moreover, where the pyrolysis products are quenched, as by spraying oil into the separation device, high molecular weight pitch molecules deposit on the walls of the separator, or pass out of the separator and deposit in downstream apparatus. In either case, removal of the high molecular material is an expensive operation.

In a large number of prior techniques the heat necessary for pyrolysis has been furnished by burning the solid coke or char produced. The most usual technique is to withdraw solid pyrolysis product from the reaction zone where it is formed, and burn part of it in a heater, and often in a fluidized bed, to heat the unburned remainder which is then reburned to the reaction zone.

This technique is open to several objections. The ash produced contains oxides of vanadium, nickel and iron. Since the unburned solids are continuously recirculated, this ash and the oxides contained therein build up in the system and cause serious problems of corrosion, particularly at temperatures of say 1400° F. and above.

In addition to problems of corrosion, concentration of metallic oxides in the fluidized solids causes very serious difficulties of temperature control. Thus at a reactor temperature of say 1400° F., and under the reducing conditions maintained in the reactor, the metal oxides give up a substantial portion of their oxygen. They are later reoxidized in the heater. The oxidation reaction in the heater is highly exothermic and the reduction reaction in the reactor is endothermic, causing the heater to overheat excessively and the reactor to cool off excessively, and making it difficult to maintain a proper temperature in the reactor without having the heater operate at an excessively high temperature.

It has also been found that the reduced oxide containing particles formed in the reactor tend to stick to each other and to the reactor surfaces, causing difficulties in fluidization.

It may further be pointed out that while prior pyrolysis systems of the types described have been utilized to treat petroleum residues, to present knowledge no attempt has been made to replace basic refinery equipment, such as atmospheric and vacuum distillation equipment or thermal and catalytic cracking equipment with such systems. This is so despite the fact that such conventional basic equipment presents a very large cost element, particularly in smaller plants of say 5000 to 50,000 bbl./day capacity.

It is an object of the present invention to provide a more economic method and apparatus for the production of high value solid, liquid, and gaseous products from low value hydrocarbonaceous materials, than has hitherto been available.

It is a further object of the invention to provide a method and apparatus of the class described in which a maximum amount of liquid aromatic products can be obtained.

It is another object of the invention to provide an economic method and apparatus of the class described using a mass of finely divided solid carbonaceous materials.

It is a further object of the invention to provide a process and apparatus of the class described in which the necessary heat can be drawn from the combustion

of coke formed during the process, under conditions which are more easily controlled than has hitherto been possible.

It is a further object of the invention to provide a method and apparatus of the class described in which the necessary heat can be drawn from the combustion of coke formed during the process, under conditions which are more easily controlled than has hitherto been possible.

It is a further object of the invention to provide a method and apparatus of the class described in which various low cost fuels can be substituted for the coke produced in the process to supply the heat necessary for pyrolysis.

It is a further object of the invention to provide a method and apparatus of the class described in which the conditions of pyrolysis may be changed with comparative ease.

It is a further object of the invention to provide a method and apparatus of the class described in which either hydrocarbon oil, or coal, or both, can be used as feedstock.

It is a further object of the invention to provide a method and apparatus of the class described in which successive exposure of ash-containing material to oxidizing and reducing conditions is minimized.

It is a further object of the invention to provide a process and apparatus of the class described in which corrosive oxides are easily removed from the system.

It is still another object of the invention to provide methods and apparatus for the refining of petroleum which are simpler and less expensive than those presently available.

According to the invention, these and other objects are attained by heating a hydrocarbonaceous feed stream to between about 1100° F. and about 1800° F., and preferably to between about 1100° F. and about 1700° F., to at least partially pyrolyze said feed stream by charging said feed stream to a hot moving stream of gases and entrained finely divided solids, delivering the combined stream of hot gases, solids and feed to a fluidized bed of finely divided solids and removing vaporous products of pyrolysis from said bed.

The use of a fluidized bed with its relatively constant temperature, in the manner indicated, provides a kind of thermal flywheel which permits a more stable and easily controlled pyrolysis. Thus, heavy liquid products of pyrolysis may be kept at a high easily controlled temperature for a relatively extended time without undue enlargement of equipment, until their pyrolysis is uniformly completed.

If, on the other hand, the products are quenched either by maintaining the bed at a low temperature, or by using a quenching spray as described more fully below, the fluidized bed provides a large surface area for incompletely pyrolyzed liquids to deposit upon, preventing their depositing on and fouling downstream apparatus.

The solid particles in the hot stream and in the fluidized bed, are preferably, but not necessarily, the coke or char produced by the pyrolysis. If desired, this coke may be augmented or replaced by other solid carbonaceous material such as coal, lignite, oil shale or the like, or char or coke from some external source. It is also within the scope of the invention to use a more inert material, for example, sand. Entrained in the moving stream, the solid particles serve to bring the stream gases to the desired temperature, either by heating or by cooling them. The particles also provide a surface upon which coke, formed by pyrolysis of the feed, can deposit.

The hydrocarbonaceous materials which can be used as feed in the novel process include such materials as, for example, coal, oil shale, lignite, peat, residual fuel oils such as Bunker C fuel oil, coke oven by-product tar, crude oil, reduced crude oil, virgin distillate gas

oils, catalytic recycle gas oils, kerosenes, naphthene, and lower paraffins having two or more carbon atoms in the molecule, such as propane, butanes, and ethane.

The gaseous stream containing entrained solids into which the hydrocarbon feed is introduced, may be derived from several sources. Where the primary purpose is to produce a high heating value utility gas, the entraining gas is preferably one which may easily be separated from the gaseous products of pyrolysis, or else which will not detract from the value of the product. Such gases may for example be steam or recycled product gas.

Where, on the other hand, a diluted product gas is acceptable, the entraining gases may be products of combustion, e.g. CO₂, and/or nitrogen.

The temperature at which the pyrolysis is conducted will vary to some extent with the materials being reacted and with the products desired. Generally, however, as indicated above, it will be between about 1100° F. and about 1800° F., preferably between about 1100° F. and about 1700° F. Pressure is not considered critical and may be atmospheric or as high as, for example, 2050 p.s.i.g. Reaction time may vary from say about 0.1 to about 5 seconds.

Preferably, the heat necessary for pyrolysis is furnished by burning finely divided coke or char produced in the pyrolysis reaction. In a preferred form of the invention, the coke is burned in a slagging type combustion device. By this is meant a combustion device so designed that the ash is converted to a liquid slag which may be drained away, rather than passing off overhead to gather in downstream products and apparatus. Such combustion devices include those having cyclonic combustion chambers in which the finely divided fuel is burned in a vertically moving body of hot gases. Furnaces of this type are well known in the art and are described, for example in Patents Nos. 836,145, 836,219, and 2,357,301. They are commonly referred to as cyclone furnaces. Where the solid material entrained in the gases prior to feed introduction is not carbonaceous, it will of course not be possible to use a slagging type burner.

It is also within the scope of the invention to obtain the heat necessary for pyrolysis in whole or in part from sources other than the coke produced. Thus, where the coke has a sale value higher than available external fuels, it may be recovered and in its place the cheap external fuel may be burned in any type of a conventional burner. In certain cases, the value of the coke may be higher than the fuel gas produced by pyrolysis and there the fuel gas may be burned in place of or in partial replacement of the coke.

The way in which the heat of pyrolysis is transferred from its source to the hydrocarbonaceous feed varies. Preferably, however, where the solid products of pyrolysis are burned to produce the necessary heat, no portion of the solids introduced into a zone where substantial oxidation takes place is reintroduced into the reaction zone. In this way, building up of metal oxides in the system is avoided. In one embodiment, hot gaseous products of combustion drawn from a burner are made to entrain finely divided solids having a lower temperature than the hot gases, and it is to this stream that the hydrocarbonaceous feed is added. This embodiment is simple and direct and requires a minimum of equipment.

In a second embodiment, hot gaseous products of combustion drawn from a burner are used to heat up a mass of finely divided solids, which is then separated from the products of combustion and entrained in another stream of gases to which is charged the hydrocarbonaceous feed. This other gas stream may be, for example, steam or recycled product gas. The second embodiment has the advantage of avoiding contamination of the gaseous products of pyrolysis by inert components such as CO₂. Such contamination would result were the hot products of combustion brought directly into contact with the feed.

In either form of the invention, the hydrocarbon feed may be preheated before introduction into the hot moving stream of gases and entrained solids. In either form, the burner may be fired with solid products of pyrolysis removed from the fluidized bed.

It may be pointed out that the pyrolysis of hydrocarbonaceous materials comprises an initial endothermic phase and a final exothermic phase. In the endothermic phase, the hydrocarbonaceous feed is converted into substances believed to consist of free radicals and unsaturated compounds, which have higher enthalpies than the final products. In the second stage, these intermediate high enthalpy substances recombine to form the final products and in so doing release heat.

In the present process, the initial endothermic phase of the cracking reaction may be carried out before the mixture of the gases and solid particles reaches the fluidized bed, and the exothermic portion may then be carried out in the fluidized bed. With this arrangement, the heat of reaction aids in maintaining the bed, with its relatively large cross-sectional area and volume, at reaction temperature.

Alternatively, both portions of the reaction may be carried to completion before the reactants reach the fluidized bed and the bed may be maintained at a relatively low temperature to quench the reaction products and prevent the formation of undesirable materials. By quenching in this manner, pitch-like substances of high boiling points are condensed on the particles of coke, and are thus removed from the overhead stream where they would tend to deposit in transfer lines and in subsequent distillation equipment. If necessary, the temperature of the bed may be maintained constant by withdrawing solid material from the bed, heating or cooling it, as in a heat exchanger, and returning it to the bed. It is, of course, also possible to have either the endothermic or the exothermic parts split between the reaction stream and the fluidized bed.

In another aspect of the invention, especially useful where a relatively heavy hydrocarbonaceous feed, such as Bunker C fuel oil or coke oven tar is charged to a hot moving stream of gases and entrained solids, materials having a high molar H/C (hydrogen/carbon) ratio, relative to the hydrocarbonaceous feed, may be added to the hot stream before the feed itself is introduced. Such materials may include, for example, hydrogen, or hydrocarbons such as methane, ethane, ethylene, propane, propylene, and butane. By using such additions, the proportion of lower boiling materials in the pyrolysis product is increased and the proportion of pitch is decreased. In particular where butane is used, the proportion of valuable butadiene is increased. In addition, sulphur which would normally remain in the coke or char residue is carried overhead as H₂S, increasing the value of the char or coke.

The materials added may be obtained from sources outside the pyrolysis system. However, the fixed gases produced by pyrolysis contain materials having a high H/C ratio and preferably these gases, or a portion of them, are recycled and added to the hot stream.

Except in the case where the material added consists principally of hydrogen, it is generally desirable to inject the added material at a point on the hot gaseous entrained solids stream where the temperature of the hot stream is sufficient to at least partially crack the added substance, for example at between about 1500° F. and about 1700° F. In this way, additional valuable products are formed and a high partial pressure of hydrogen is created in the zone where pyrolysis of the main feed material is to be carried out. A high partial pressure of hydrogen enhances the effects noted above, namely a decrease in the production of pitch, an increase in the quantity of lower boiling materials, and a more valuable residue.

It is also within the scope of the invention, where the

pyrolysis is carried out in a moving stream of gases and entrained solids, and the combined stream is subsequently delivered to a fluidized bed, to at least partially quench the reacted stream by spraying a quenching medium into the stream just before it is introduced into the fluidized bed. This medium may be water, but is preferably a liquid hydrocarbon, such for example as gas oil. The amount of oil is preferably regulated so that the gases will remain at a temperature sufficient to crack the sprayed oil itself, thus adding to the quantity of desirable vapors removed from the separating zone.

5 The pyrolysis methods which have been outlined are applicable to many industries. In particular, the invention comprises a method of refining petroleum in which crude oil is topped to remove gasoline and then subjected to the pyrolysis methods described above.

10 The invention further includes an apparatus for the pyrolysis of hydrocarbonaceous materials which comprises in combination, an enlarged vessel adapted to support a fluidized bed of finely divided solids, a conduit leading to said enlarged separatory vessel, means comprising a slagging type combustion device connecting with said conduit for generating a hot stream of gases containing entrained solids, and means for introducing a hydrocarbonaceous feeding into said conduit.

15 The invention further includes an apparatus for the pyrolysis of hydrocarbonaceous materials which comprises in combination, an enlarged vessel adapted to support a fluidized bed of finely divided solids, a conduit leading to said enlarged separatory vessel, means comprising a slagging type combustion device connecting with said conduit for generating a hot stream of gases containing entrained solids, and means for introducing a hydrocarbonaceous feeding into said conduit.

20 More specifically, in one embodiment, the invention provides apparatus comprising, in combination, a conduit, a slagging type burner having a hot gas outlet connected to one end of the conduit, an enlarged vessel adapted to support a fluidized bed of finely divided solids connected to the other end of said conduit, means for introducing finely divided solids at a point along the length of said conduit and means for introducing a hydrocarbonaceous material to said conduit at a point between 25 the point of introduction of solids thereto and the end of the conduit joined to said vessel.

25 In another embodiment, apparatus according to the invention comprises a first separatory vessel, a second separatory vessel adapted to support a fluidized bed of finely divided solids, first conduit means for transferring solids from said first to said second vessel, means for introducing a hydrocarbonaceous feed into said conduit, a slagging type combustion device, second conduit means joining said combustion device with said first separatory vessel, means for introducing solids from said second separatory vessel to said second conduit means and means for conveying solids from said first separatory vessel to said burner.

30 In both embodiments, the conduits may have Venturi constrictions or throats at the point where the hydrocarbon feed is introduced.

35 By choice of proper conditions of operation and feedstock, a great variety of valuable products can be produced, including ethylene, propylene, butylenes, butadiene, cyclopentadiene, gasolene, benzene, toluene, xylene, naphthalene, resin-formers, creosote oil, electrode-grade pitch, and coke, and synthesis gas for the product of ammonia, methanol, synthetic fuels, and the like.

40 In the detailed description which follows, reference will be made to the accompanying drawings in which:

45 Fig. 1 is a schematic flow diagram of one type of pyrolysis system according to the invention wherein hot gaseous products of combustion are brought into direct contact with the hydrocarbonaceous feed.

50 Fig. 2 is a schematic flow diagram of a second type of pyrolysis system according to the invention, in which heat is transferred to the hydrocarbon feed by means of finely divided solids.

55 Fig. 3 is a schematic flow diagram showing elements of a preferred type of petroleum refining system using the pyrolysis system of Fig. 2, and

60 Fig. 4 is a schematic flow diagram showing elements of another type of petroleum refining system also using the pyrolysis system of Fig. 2.

65 Referring first to Fig. 1, a pyrolysis system, according

to one embodiment of the invention, may comprise a U-shaped conduit 3 extending between a cyclone burner 4 and an enlarged separation vessel, or gasifier 5, suitable for containing a fluidized bed of finely divided solids 6.

A line 7, having a valve 27, is provided for feeding solids from the bed 6 to the burner 4. A line 8 is provided for introducing oxygen, air, or other oxygen-containing gas to the burner 4. The burner has a draw-off 28 for liquid slag.

A line 9 is provided for introducing finely divided solids from the bed 6 to the conduit 3 at a point 10 downstream from the connection between the conduit 3 and the burner 4.

The conduit 3 has a Venturi throat 2 and at the throat a line 1 is connected to the conduit for the introduction of a hydrocarbonaceous feed. A preheater 11 is furnished for preheating the feed.

The gasifier 5 has an internal solids separator such as a cyclone separator 12 for further separating entrained solids from the gaseous products emanating from the bed 6. A line 13 is provided for removing such products from the vessel.

To provide a means for controlling the temperature in bed 6, a heat exchanger 16 is provided, together with a line 14 leading from the bed 6 to the heat exchanger 16. A valve 15 controls the flow through line 14. Cooled solids are returned from the heat exchanger 16 to conduit 3 by means of a line 17 and a valve 18. A line 19, having a valve 20, is provided for withdrawing solids from line 17. A line 21, having a valve 22, is arranged for the introduction of fluidizing gas into line 17.

In the preferred mode of operation, a fluidized bed 6 of finely divided solids is established in separation vessel 5. These solids are preferably coke, of the general type to be produced, but they may be other solid material, such for example as coal, lignite, or oil shale. The temperature in the vessel 5 is maintained between about 600° F. and about 1800° F., preferably between about 800° F. and about 1700° F., and the pressure between about 0 p.s.i.g. and about 2000 p.s.i.g., preferably between about 5 p.s.i.g. and about 300 p.s.i.g. A certain amount of the finely divided solid material is continuously withdrawn from the bed 6 through line 7 and is fed to the cyclone burner 4, where it is burned with air or oxygen introduced through line 8. The hot gaseous products of combustion from burner 4, at a temperature between about 1400° F. and about 5000° F., preferably between about 2000° F. and about 3200° F., enter conduit 3 and are mixed with additional carbonaceous solids withdrawn from the bed 6 through line 9. These solids enter the conduit 3 at point 10, and are entrained in the hot gases and serve to cool the gases, preferably to between about 1200° F. and about 2000° F. The pressure of the gases at this point is between about 0 p.s.i.g. and about 2050 p.s.i.g., preferably between about 6 p.s.i.g. and about 305 p.s.i.g.

The mixture of hot products of combustion from burner 4 and solid particles pass through the Venturi throat 2 where they pick up the hydrocarbonaceous feed, introduced from the line 1, after having been preheated in heater 11. Upon introduction of the feed into the conduit 3, pyrolysis is initiated.

The temperature of the materials in the reaction zone downstream of the Venturi throat is between about 1100° F. and about 1800° F., preferably between about 1100° F. and about 1700° F. The pressure is maintained between about 0 p.s.i.g. and about 2050 p.s.i.g., preferably between about 6 p.s.i.g. and about 305 p.s.i.g.

As indicated generally above, in one embodiment of the invention, the endothermic part of the pyrolysis reaction is preferably completed in the conduit 3. The exothermic part, on the other hand, may be carried out in the conduit 3 or in the gasifier 5. Where the exothermic part is carried out in the gasifier, the gasifier is operated at a temperature between about 1100° F. and about

1800° F., preferably between about 1100° F. and about 1700° F., and at a pressure between about 9 p.s.i.g. and about 2050 p.s.i.g.

Where the gasifier bed is used to quench the products of reaction, the gasifier is operated at a temperature between about 600° F. and about 1100° F., preferably between about 800° F. and about 1100° F., and at a pressure between about 0 p.s.i.g. and about 2000 p.s.i.g., preferably between about 0 p.s.i.g. and about 300 p.s.i.g. Under these conditions, further reaction of the cracked products is suppressed and the heavy pitch materials produced by the cracking reaction are condensed onto the solid particles, leaving the cracked products to pass out overhead through cyclone separator 12 and line 13. The products emerging through line 13 may be condensed and further treated, as for example by distillation steps not shown.

To maintain the bed of fluidized particles 6 at proper temperature, a stream of such particles may be withdrawn through line 14 and valve 15 and passed through a heat exchanger 16 where it is cooled. The cooled material is then returned to the bed 6 through line 17, valve 18, and conduit 3. If desired, a certain amount of this carbonaceous material may be withdrawn as product through line 19 and valve 20. To maintain the proper flow of material in line 17, a suitable fluidizing gas, such as steam, may be introduced through line 21 and valve 22.

The combustion carried out in burner 4 produces, in addition to the hot gases delivered to the conduit 3, a liquid slag which is withdrawn through off-take 28. This slag contains a large part of the corrosive oxides originally present in the coke. The use of a combustion device, producing a liquid slag, thus furnishes a convenient way to prevent such oxides from building up in the system and minimizes corrosion problems.

As noted above, the combustion-supporting gas introduced through line 8 may be either air or oxygen. With air, a fuel gas can be produced having a heating value in the neighborhood of 200 to 600 B.t.u. per cubic foot, depending on the type of material charged. Using air, the production of materials such as acetylene and butadiene is favored because the diluting effect of the nitrogen results in a lowered partial pressure of hydrocarbon. Such lower partial pressure favors net formation of unsaturated compounds because of the reduced chance for polymerization due to the lowered concentration.

If it is desired, on the other hand, to have the product gas high in B.t.u. content, e.g. 600-1500 B.t.u. per cubic foot, or have it most suitable for the recovery of ethylene, oxygen should be used instead of air at point 8. The use of oxygen to support combustion in the cyclone burner 4 obviates compressing a product diluted with nitrogen to the 500 to 700 pounds per square inch necessary to separate the ethylene from other gases present.

In bringing the apparatus shown in the drawing on stream, steam may be introduced through line 8 and finely divided coke having a particle size between about 10 microns and about 0.1 inch introduced through line 23 and valve 24. When the bed 6 has been filled to a sufficient depth, air or oxygen is introduced through line 8 and additional coke is introduced to the conduit 3, through line 24 and valve 25. Only sufficient oxygen or air is introduced to supply the proper amount of heating. Excess oxygen or air is avoided. Hydrocarbon feed is then slowly introduced through line 1. The hydrocarbon is converted into coke in the conduit 3 and bed 6 builds up in the gasifier 5. The carbon introduced through valves 24 and 25 is then gradually reduced and valves 26 and 27 are opened to permit carbon particles from the bed 6 to flow through lines 7 and 9 and thence into the cyclone burner 4 and conduit 3 respectively.

As indicated above, the system described has great flexibility of operation. Thus for example, solid materials may be charged through line 30 and admixed with a gas or liquid introduced through line 1 to the preheater

11. Such solids may include hydrocarbonaceous material such as coal, lignite, peat, oil shale, or even an inert material such as sand. Materials such as coal, introduced in this manner, may be carbonized in the duct 3 and separation vessel 5 to give gaseous products and a coke or char. Depending on the quantity of oxygen present in the separation vessel, a certain amount of gasification to carbon monoxide may also occur.

Where the solid is non-carbonaceous, it forms an inert base for the coke produced from the liquid or gaseous material to deposit on. In this instance, it is desirable to use a combustion device other than the slagging type burner shown in the drawing.

It is possible to dispense entirely with preheater 11, closing off valve 34 and charging fluid feed through line 30 and solid material through line 31.

If desired, the hydrocarbonaceous material charged to the system may be entirely solid material. In this event, valve 34 is closed and the coal or similar solid hydrocarbonaceous feed material is charged to duct 3 through line 31, steam and other inert gas being introduced through line 33 to move the finely divided solid to the duct 3.

A further embodiment of the invention is shown in Fig. 2. As shown in that figure, a system according to the invention may comprise a gasifier 100 having an upper enlarged separating section 121 of more or less cylindrical shape and an elongated, tapered leg 101. The upper portion 121 is adapted to support and contain a fluidized bed of finely divided solids 106. Adjacent the gasifier 100 are a burner, such as a slagging-type cyclone burner 102 and a cyclone separator 103. A duct 104 leads from the exhaust end 105 of the burner 102 to the cyclone separator 103. The burner has an air inlet 107 and an outlet 108 for liquid slag. A transfer line 109 for fluidized solids leads from the bed 106 in gasifier 100 to the duct 104. A line 110 is provided to supply fluidizing gas, such as steam, to the line 109 to maintain the solids being transferred through that line in fluidized condition and to aid in conveying the solids.

A line 111 extends from the bottom of cyclone separator 103 to the bottom of the leg 101 of the gasifier 100 to enable solids to be transferred from the cyclone to the gasifier. Inert fluidizing gas, e.g. steam, may be furnished for this transfer, through lines 112 and 113, located on line 111 and at the bottom of leg 101, respectively. A line 122 is provided just downstream from line 112 for the introduction of material having a high H/C ratio, such as recycled product gas. A feed line 114 for hydrocarbonaceous material is located at the bottom of leg 101 downstream from line 122. Sprays 124, fed through a line 123 are furnished at the bottom of the enlarged section 121 of gasifier 100 for supplying oil to quench the materials being delivered to the section 121 through leg 101.

A line 115 extends between the cyclone separator 103 and the burner 102 for furnishing solids to the cyclone burner. The inlet 119 for the line 115 is preferably arranged on the wall of the cyclone 103, some distance up from its vertex, so that the solids furnished to the burner 102 are preferably larger than those drawn off the vertex of the cyclone for delivery to the gasifier 100.

A draw-off line 116 is provided for removing some of the solids moving through line 115 where it is desired to recover coke as a product.

In a preferred method of operating the system illustrated in Fig. 2, a bed 106 of carbonaceous solids, such as coke or char having a particle size between about 10 microns and about 0.1 inch is established in the upper section 121 of the gasifier 100. It is maintained at between about 600° F. and about 1800° F., preferably between about 800° F. and about 1700° F., the precise temperature depending on the reactants, the products desired, and whether the bed is being used to quench or to complete the pyrolysis. The pressure is kept at be-

tween atmospheric and about 200 p.s.i.g., preferably between about 5 p.s.i.g. and about 300 p.s.i.g. A certain amount of this finely divided solid material is continuously withdrawn through the line 109 and entrained in a stream of hot gases moving through duct 104. These gases are at an extremely high temperature, on the order of between about 1400° F. and about 5000° F., usually from about 2000° F. to about 3200° F. and serve to heat the solids to between about 1200° F. and about 2000° F.

10 The mixture of gaseous products of combustion and entrained solids are carried through duct 104 to cyclone separator 103. Here the solids are separated from the gases. The latter pass out of the separator 103 through line 117, after which they may be delivered to heat recovery equipment not shown.

15 Solids are removed from cyclone 103 in two streams. One stream, having on the average larger particles than the other, is withdrawn through line 115 and at least a major fraction of it is carried to line 107 where it is entrained in a stream of air and charged to the burner 102. Another fraction may be removed from line 115 through line 116 as product.

20 In the burner 102, a combustion of the carbonaceous solids occurs with the production of a stream of hot gases which are fed into duct 104, and a liquid slag, which is drawn off through line 108.

25 The second stream of solids removed from separator 103 is drawn off the bottom of the separator and carried through line 111 to the bottom of leg 101 of the gasifier 100. An inert gas, such as steam, may be delivered to the line 111 through line 112 to maintain the solids in fluidized condition.

30 As pointed out above, it may be desirable to introduce recycled product gas or other material having a higher H/C ratio than the main feed into the pyrolysis zone to increase the proportion of lower boiling substances, at the expense of liquid pitch and reduce the sulphur content of the solid pyrolysis residue. Such materials may be introduced through line 122.

35 The gas is also introduced into the bottom of leg 101 to convey the hot solids past feed line 114, up leg 101, and into upper separating section 121. This gas is usually inert. However, where it is desired to effect gasification of the hydrocarbonaceous material, the gas introduced through line 113 may, however, contain air or oxygen.

40 Hydrocarbonaceous material, liquid, gas or solid, is fed into the moving stream of hot entrained solids through line 114 at the bottom of leg 101. This material is raised to pyrolysis temperature, i.e. to from about 1100°

45 F. to about 1800° F., preferably to between about 1100° F. and about 1700° F., by the heat from the solids moving through line 111. Under these conditions, the hydrocarbonaceous feed is pyrolysed to give gaseous products which are drawn off through a separation device 120 and line 118, and coke or char which in part deposits on the particles introduced from line 111, and in part forms new particles.

50 The gaseous products removed through line 118 may be treated in a variety of ways, not shown, to recover their valuable components. The solids are withdrawn through line 109 as indicated above.

55 As in the embodiment of Fig. 1, great flexibility is possible in the conditions under which the system shown in Fig. 2 may be operated. Thus, the gasifier may be operated so that the endothermic portion of the pyrolysis takes place in leg 101 and the exothermic portion in the fluidized bed 106. In such arrangement, the heat released during the exothermic phase helps to maintain the temperature of the fluidized bed at reaction level.

60 Alternately, both portions of the pyrolysis can be carried out in the leg 101 and the bed 106 can be used to quench the hot vapors produced below, as explained above in connection with Fig. 1. If desired, a part of the quenching may be accomplished by means of oil, e.g. gas oil, supplied through sprays 124 and line 123.

Spraying oil at this point not only quenches the products of pyrolysis, but also permits cracking of materials such as gas oil, which may themselves have been produced by the pyrolysis. The amount of oil used is preferably limited to not more than that which will bring the temperature of the gases down to the cracking temperature of the oil being sprayed, e.g. to not less than 800° F. and preferably to 800-1200° F., where the sprayed oil is gas oil.

The composition of the hydrocarbon feed charged through line 114 is subject to the same wide variation, which has been described in connection with Fig. 1.

As indicated above, the pyrolysis method and apparatus which have been described may be used with great advantage in the refining of petroleum. Two refining systems employing the novel method and apparatus are shown schematically in Figs. 3 and 4.

Referring to Fig. 3, a refining system according to the invention may comprise a pyrolysis unit indicated generally as 200, and a fractionator 201. The pyrolysis unit 200 is of the general type discussed above in connection with Fig. 2 and comprises a gasifier 202 having an enlarged upper section 203 suitable for supporting a bed of fluidized solids, and an elongated tapered lower leg 204, a cyclone burner 205, a cyclone separator 206, and a duct 207 connecting the burner 205 and the separator 206 with the bottom of the leg 204. A solids draw-off chamber 209 is provided on a wall of the upper portion 203 of gasifier 202 and a line 210 connects this draw-off chamber with the duct 207. An air inlet line 211 is provided for burner 205. A solids draw-off chamber 212 is provided on a wall of cyclone separator 206 and a line 213 connects this draw-off chamber with the air inlet line 211 to the burner 205. A line 214 is provided for removing gases from separator 206.

An internal cyclone 215 having a dip leg 216 is mounted in the upper section 203 of gasifier 202 and a line 217 is provided to receive the gases discharged from gasifier 202 through this cyclone 215.

Fractionator 201 has an upper section 218 and a lower section 219, separated by an accumulator pan 220 having a chimney 220a. Each section contains a number of trays 221. The number and design of these trays depends on various factors, such as the composition of the feed, and are readily calculated by those skilled in the art.

A heat exchanger 222 is set up adjacent the fractionator 201 and a line 223 is provided for furnishing fluid from a tray in the bottom section 219 of the fractionator to the heat exchanger. A line 224 is arranged to return at least a portion of this fluid to the fractionator and a line 225, connecting with this line 224, permits a portion of the fluid to be withdrawn after passing through the heat exchanger 222.

A line 226 for crude oil feed passes through heat exchanger 222 and discharges to the upper section 218 of the fractionator. A line 227 is provided for delivering liquid from the accumulator pan to the bottom of the leg 204 of gasifier 202. A line 228 is provided for withdrawing residue from the bottom of the lower section 219 of the fractionator. This line 228 has a branch 229 which joins the line 227, permitting at least a portion of the residue from the bottom of fractionator 201 to be charged to the leg 204 of the carbonizer. Another branch 230 of line 228 leads back to the lower portion 219 of the fractionator, quenching the gaseous products of gasifier 202 discharging through line 217.

In operation, a fluidized bed of finely divided carbonaceous material, such as the coke produced in the process, is maintained in the upper section 203 of carbonizer 202. This bed is maintained at a temperature between about 600 and 1800° F., preferably between about 800 and about 1800° F., by withdrawing coke produced therein through line 210, separating it from entraining gases in separator 206 and burning a part of

the separated coke in burner 205, all as described above in connection with Fig. 2.

Crude oil is introduced through line 226. It is pre-heated in heat exchanger 222 and charged to the upper section 218 of fractionator 201. There, gasoline and lower boiling components are removed overhead through line 231. The residual liquid collects on accumulator pan 220 and is charged through line 227 to the leg 204 of gasifier 202. Here it meets a stream of inert gas, such as steam, introduced through lines 232 and 233, and hot entrained solid coke particles, and is pyrolysed in the leg 204, or in the leg 204 and in the fluidized bed 234 to give coke and a mixture of gas oil, gasoline containing some aromatics, and fixed gases containing a high proportion of ethylene and other olefins. These products are removed through cyclone 215 and line 217 and meet the residuum from fractionator 202 flowing through line 230 which serves to quench the high temperature gases. The combined stream of gases and residue is returned to the lower section 219 of fractionator 201 where further separation is carried out.

A side stream comprising naphthalene oil can be withdrawn from the lower section 219 of the fractionator through line 223 and used to heat the crude in heat exchanger 222. A part of this naphthalene oil can then be withdrawn through line 225 and the balance returned to the fractionator through line 224.

A part of the fuel oil residue from the lower section 219 of fractionator 201 can be charged to the gasifier through branch 229 of line 228. Another part may be withdrawn as product through line 235.

Another system for refining petroleum according to the invention is shown in Fig. 4. Again the system comprises a pyrolysis unit 300 and a fractionator 301. The pyrolysis unit is similar in construction to that shown in Fig. 3. It comprises a gasifier 302 having an enlarged upper section 303 and an elongated lower leg 304, a separator 306 and a burner 305. A duct 307 is provided for delivering hot gases from burner 305 to separator 306, and a line 313a is arranged to deliver solids from separator 306 to burner 305 for use as fuel. Air or oxygen may be fed to burner 305 through line 311a. A line 308 carries hot solids from the separator 306 to the gasifier 302 and a line 310 carries solids from the gasifier to duct 307. A line 337 is provided for supplying a gas having a high H/C ratio, such as recycled product gas, to the gasifier 302.

The fractionator 301 comprises a number of bubble trays 311 of conventional design. A line 312 connects the top of gasifier 302 to a point near the bottom of fractionator 301. A line 313 is provided for introducing crude oil into line 312. Another line 314 connects the bottom of fractionator 301 with the bottom of gasifier leg 304. A gas oil side stream may be drawn off fractionator 301 through line 315. A part of the gas oil may be sprayed through sprays 335 to quench the hot products of pyrolysis and crack the gas oil. The overhead from the fractionator is removed through line 316.

In operation, a fluidized bed 334 is established in the upper section 303 of gasifier 302 as described above in connection with Figs. 2 and 3. Crude oil is charged through line 313 and serves to quench the hot gases emanating from the carbonizer. The combined stream is delivered to fractionator 301 where a gaseous stream, comprising fixed gases and gasoline, is removed overhead. Gas oil is removed as a side stream through line 315. A portion of this material is delivered to sprays 335 where it serves to partially quench the hot products of pyrolysis to say 800-1200° F. and is itself cracked to gasoline. The bottoms from the fractionator, comprising all components of the crude oil boiling above about 350° F. are sent through line 314 to the bottom of carbonizer leg 304 and into the fluidized bed 334. Recycled product gas may be added to the charge to bed 334 through line 337.

Pyrolysis of the residue occurs under the influence of the hot solids, breaking down the residual crude oil into coke, gas oil, gasoline, and fixed gases. The gaseous products are removed from the gasifier through line 312 and carried back to the fractionator as described above.

The following examples are given for purposes of illustration only, and are not to be taken as in any way limiting the invention beyond the scope of the appended claims.

Example I

Using the apparatus of Fig. 1, 750 barrels per hour of a Bunker C fuel oil are introduced into preheater 11 and heated to about 600° F. About 20,000 pounds per hour of coke are burned with air in the burner 4 to give a temperature at the outlet of the burner of about 3000° F. About 600,000 pounds per hour of coke are introduced at point 10 into conduit 3 to cool the hot gases from the heater to a temperature of about 1600° F. The temperature in the gasifier 5 is maintained at about 1200° F. About 85,000 standard cubic feet per minute of volatile products are withdrawn through line 13, having the following approximate analysis

	Weight percent
Oil gas	25
Aromatic liquids	20
Combustion products	55
	100

200 pounds per hour of coke are withdrawn through valve 20.

Example II

The procedure described in Example I is carried out except that oxygen instead of air is introduced through line 8. The temperature at the outlet of the burner is about 4000° F. The temperature just upstream from the Venturi throat 2 is about 1700° F. and the temperature in the gasifier is about 1150° F. The product removed through line 13 analyzes approximately as follows:

	Weight percent
Oil gas	40
Aromatic liquids	30
Combustion products	30
	100

5000 pounds of coke per hour are withdrawn through valve 20.

Example III

The process described in Example I is carried out, but about 17,000 standard cubic feet per minute of propane are used as the hydrocarbon feed. Approximately 3000 standard cubic feet per minute of fuel gas are introduced to the cyclone burner, with sufficient air for combustion. The temperature at the outlet of the burner is about 3200° F. About 400,000 pounds per hour of coke are removed from the gasifier through line 9 and introduced into the conduit at 10. The temperature just upstream from the Venturi throat 2 is about 1800° F. The temperature in the bed 6 is about 1400° F. A small amount of coke is intermittently removed through line 20. About 65,000 standard cubic feet per minute of gaseous product are removed through line 13, analyzing approximately as follows:

	Weight percent
Oil gas	45
Aromatic liquids	5
Combustion products	50
	100

Example V

About 100 barrels per hour of a heavy Bunker C fuel oil are introduced into heater 11 in the system of Fig. 1, and heated to about 600° F. 100 tons per hour of

coal are added through valve 31 and the mixture is introduced into the system at point 2. About 80 tons per hour of coke are gasified in burner 4 using about 50,000 standard cubic feet per minute of a mixture of oxygen and steam in about equal proportions, giving a temperature at the outlet of about 2500° F. About 300,000 pounds per hour of coke are introduced at point 10 into conduit 3 to cool the hot gases from the heater to a temperature of about 1600° F. The temperature in the gasifier 5 is maintained at about 700° F. in order to quench the gaseous products, to remove unstable compounds by reaction and to remove heavy pitches by condensation onto the coke.

About 100,000 standard cubic feet per minute of volatile products are withdrawn through line 13, having the following approximate analysis:

	Weight percent
Oil gas	12.5
Aromatic liquids	7.5
Partial combustion products	80.0
	100.0

The partial combustion product contains over 30% hydrogen.

Example V

1000 barrels per hour of a Bunker C fuel oil are introduced into the system of Fig. 2. About 3,510,000 pounds per hour of coke are withdrawn from the gasifier 100 and charged to duct 104. 55,100 pounds per hour of this coke are charged to burner 102 where they are burned with air to give a liquid slag and hot combustion products, and 3,440,000 pounds per hour are recycled through line 111. 27,000 gallons per hour of gas oil are sprayed through sprays 124 into bed 106. The temperature in the gasifier bed is about 1300° F. About 66,000 standard cubic feet per minute of water-free volatile products are withdrawn through line 118, having the following approximate analysis:

	Weight percent
Oil gas	47
Aromatic distillates	21
Pitch	32
	100

Example VI

The conditions of Example V are repeated, except that additional fuel oil is burned in burner 102 to supplement the heat obtained from burning product coke, and about 37,000 standard cubic feet per minute of recycled product gas having the following composition:

	Percent
H ₂	30
CH ₄	65
Heavier gases	5

are charged through line 122. The resulting volatile products withdrawn through line 118 have the following composition (on a recycle-gas free basis):

	Weight percent
Oil gas	55
Aromatic distillate	23
Pitch	22
	100

Example VII

100,000 pounds per hour of bituminous coal, having the following approximate analysis:

	Weight percent
Carbon	76
Ash	8
Volatile combustible matter	26
	100

are introduced through line 114 into the system of Fig. 2. Steam is used as the fluidizing and conveying medium in line 113. The temperature of the gasifier bed is kept at 1300° F. 76,000 pounds per hour of char are drawn from cyclone 103 and returned via line 111 to the gasifier.

The water-free gaseous product removed through line 118 amounts to around 520,000 standard cubic feet per hour and has the following approximate analysis:

	Weight percent
Coal gas	73
Aromatic liquids	27
	100

Example VIII

1000 bbls. per hour of a 38° API mid-continent crude oil containing about 32% reduced crude after atmospheric distillation, is fed through line 226 into fractionator 201 in the apparatus of Fig. 3. 600 bbls. per hour of topped crude is removed from accumulator pan 220 and charged to pyrolysis unit 200 along with 50 bbls. per hour of the fuel oil bottoms removed from the lower section 219 of fractionator 201. A fluidized bed of petroleum coke at a temperature of about 1100° F. and pressure of about 25 p.s.i.g. is maintained in carbonizer 202. Total products obtained are (wt. percent of the crude):

	Weight percent
Gas (ethylene about 24%; propylene and heavier, 18% by volume)	36
Gasoline	30
Naphthalene oil	1
Fuel oil (viscosity equivalent to ASTM #6)	16
Coke	7
	100

Example IX

1000 bbls. per hour of the same crude used in Example VIII are charged through line 313 in the system of Fig. 4. 400 bbls. per hour of bottoms from the fractionator 301 are fed to gasifier 302. A fluidized bed of coke is maintained in the gasifier at a temperature of about 1100° F. and a pressure of about 25 p.s.i.g. 250 bbls. per hour of gas oil are recycled through line 336 and sprays 335. Total products obtained are (approx. wt. percent of the crude):

	Weight percent
Gas (18-25% ethylene and up to 50% total olefins)	15
Gasoline	45
Gas oil	28
Coke	12
	100

Example X

Example IX is repeated except that 14,800 standard cubic feet per minute of recycled product gas having the following composition:

	Percent
H ₂	30
CH ₄	65
Heavier gases	5

are introduced into the bed 334 through line 337. Total products obtained are:

	Weight percent
Gas (25% ethylene and up to 60% total olefins)	18
Gasoline	46
Gas oil	28
Coke	8
	100

From a consideration of the foregoing description, it will be seen that the invention provides a simple, direct, versatile and economical method and apparatus for the

production of gaseous, liquid, and solid products by pyrolysis of hydrocarbonaceous materials. Only one fluidized bed is required so that the initial cost is lower and maintenance is reduced as compared with prior systems. The necessary heat can be furnished by combustion of the coke produced, and this combustion is carried out under conditions which are flexible and easy to control, and which permit corrosive oxides present in the fuel to be removed from the system. Pyrolysis of the hydrocarbonaceous feed is done under conditions where deposition of coke on heat transfer surfaces is not a problem.

The process described is inherently flexible in that the time and temperatures of reaction can be readily and independently adjusted by varying the length of the conduit, and the temperatures both in the conduit and in the separation zone. This ability is valuable especially where it is desired to produce in optimum amounts the most valuable products by feeding stocks of varying character at different points along the conduit, and where it is desired to produce certain relatively unstable compounds such as butadiene, which require that the material be very quickly brought up to temperature, cracked for a relatively short time, and then quenched below the temperature at which these compounds will react with other material present, or polymerize.

The novel process is valuable in many industries. In particular, as in the forms illustrated above, it can be used with great economy in petroleum refineries of moderate size.

What is claimed is:

1. A process for the pyrolysis of hydrocarbonaceous material which comprises charging a feed stream of hydrocarbonaceous material into a hot moving reaction stream of gases and entrained finely divided carbonaceous solids to heat said stream to between about 1100° F. and about 1800° F. and to at least partially pyrolyse said feed stream, delivering the combined feed and reaction streams to a fluidized bed of said finely divided solids, removing vaporous products of pyrolysis from said bed, removing carbonaceous solids from said bed, burning a first portion of the solids removed from said bed in a combustion zone apart from a second portion of said solids removed from the bed to give hot gases and an ash residue, removing at least a portion of said residue from the process, contacting the second portion of the solids with the hot gases produced in said combustion zone to reheat said second portion, and using the solids so reheated in forming said reaction stream.

2. The method claimed in claim 1 and in which the overall pyrolysis reaction has an endothermic part and an exothermic part, and comprising conducting the endothermic part of the pyrolysis reaction in the reaction stream and the exothermic part in the fluidized bed.

3. The method claimed in claim 1 and comprising adding to the reaction stream a material selected from the group consisting of hydrogen and hydrocarbonaceous materials having a higher H/C ratio than the hydrocarbonaceous feed.

4. The method claimed in claim 1 and comprising contacting the reaction stream with a quenching medium immediately prior to delivery to the fluidized bed.

5. The method claimed in claim 4 wherein the quenching medium is a hydrocarbonaceous material and is itself at least partially cracked during the quenching process.

6. The method claimed in claim 1 wherein the reaction stream is moved upwardly into the fluidized bed.

7. The process claimed in claim 1 in which the solids are burned under conditions such that a liquid slag is formed.

8. A process for the pyrolysis of hydrocarbonaceous materials which comprises charging a feed stream of hydrocarbonaceous material into a hot moving reaction stream of gases and entrained finely divided carbonaceous solids and thereby heating said feed stream to between

about 1100° F. and about 1800° F., and at least partially pyrolysing said feed stream, delivering the combined feed and reaction streams to a fluidized bed of finely divided solids, removing vaporous products of pyrolysis from said bed, removing a first stream of solids from said bed, burning said first stream of solids in a combustion zone to form a high temperature stream of gaseous products of combustion and an ash residue, removing at least a portion of said residue from the process, removing a second stream of solids from said bed and entraining solids from said second stream in said high temperature stream of gaseous products of combustion to form said reaction stream.

9. A process for the pyrolysis of hydrocarbonaceous material which comprises charging a hydrocarbonaceous feed material into a first moving reaction stream of gases and entrained, hot, finely divided carbonaceous solids and thereby heating said feed to between about 1100° F. and about 1800° F. and causing at least partial pyrolysis of said hydrocarbonaceous material, delivering the combined feed and reaction stream to a fluidized bed of finely divided solids, removing vaporous products of pyrolysis from said bed, removing a stream of solids from said bed and entraining said solids in a second moving stream of hot gases, to heat said solids, delivering said second moving stream of hot gases with the heated solids entrained therein to a separating zone, removing hot solids from said separating zone and burning said solids in a combustion zone to produce said second moving stream of hot gases and an ash residue, removing at least a portion of said residue from the process, removing additional hot solids from said separating zone and entraining said additional solids in a stream of gases to form said reaction stream.

10. The method claimed in claim 9 in which the finely divided solids are solid products of pyrolysis.

11. The method claimed in claim 9 wherein the solids are burned under conditions such that a liquid slag is formed.

12. A process for the distillation of petroleum which comprises feeding crude petroleum into a first moving stream of hot hydrocarbonaceous gases, fractionating the combined stream of crude petroleum and hot gases to give a product boiling above about 350° F., charging said product to a hot moving stream of gases and entrained finely divided carbonaceous solids to heat said product to between about 1100° F. and about 1800° F. and thereby at least partially pyrolyse said product, delivering the combined stream resulting from the step last referred to, to a fluidized bed of said finely divided solids, removing vaporized products of pyrolysis from said bed, to form said first moving stream of hot gases, removing solids from said bed, burning a first portion of the solids removed from said bed in a combustion zone apart from a second portion of said solids removed from said bed to give hot gases and an ash residue, removing at least a portion of said residue from the process, contacting the second portion of the solids with the hot gases produced in the combustion zone to reheat the second portion and using the solids so reheated to form the hot moving stream of gases and entrained solids referred to.

13. A process for the refining of petroleum which comprises topping crude petroleum to remove a fraction com-

5 prising gasoline and lower boiling materials, heating said topped crude to between about 1100° F. and about 1800° F. to at least partially pyrolyse said topped crude, by charging said topped crude to a hot moving reaction stream of gases and entrained carbonaceous solid particles, delivering the resulting combined stream to a fluidized bed of said finely divided solid carbonaceous particles, removing vaporous products of pyrolysis from said bed, removing solids from said bed, burning a first portion of the solids removed from said bed apart from a second portion of the solids removed from said bed to generate hot gases and to produce an ash residue, removing at least a part of said ash residue from the process, contacting the hot gases so generated with said portion of the solids removed from said bed and thereby reheating said second portion of solids, and using the solids so reheated to form the first mentioned reaction stream.

14. The method claimed in claim 13 in which the solids are carbonaceous and are burned under conditions such that a liquid slag is formed.

15. The process claimed in claim 13 wherein the crude petroleum is topped by co-fractionation with the vaporized products of pyrolysis.

16. Apparatus for the pyrolysis of hydrocarbonaceous material comprising, in combination, a conduit having an inlet and an outlet, a slagging type combustion device having a hot gas outlet connected to the inlet of said conduit, a vessel adapted to support a fluidized bed of finely divided solids connected to the outlet of said conduit, means for conveying solids from said bed to said combustion device means for conveying finely divided solids from said vessel and introducing them into said conduit at a point along its length and means for introducing a hydrocarbonaceous feed into said conduit at a point nearer to the outlet of said conduit than the point of introduction of said finely divided solids.

17. Apparatus for the pyrolysis of hydrocarbonaceous materials comprising, in combination, a first separatory vessel, a second vessel adapted to support a fluidized bed of finely divided solids, first conduit means for transferring solids from said first to said second vessel, means for introducing a hydrocarbonaceous feed into said first conduit means, a slagging type combustion device having a hot gas outlet, second conduit means joining said hot gas outlet with said first separatory vessel, means for introducing solids from said second vessel directly into said second conduit means and means for conveying solids from said first separatory vessel to said combustion device for burning therein.
